TEMPORARY BINDER OR LOOSE SHEET HOLDER

Leon L. Allyn, Kalamazoo, Mich., assignor to
Master-Craft Corporation, Kalamazoo, Mich.,
a corporation of Michigan

Application January 24, 1938, Serial No. 186,652

10 Claims. (Cl. 129—1)

The main objects of this invention are:

First, to provide a temporary binder or loose sheet holder of the clamping bar post type in which the sheet body may be opened for effective use and at the same time has a relatively small amount of binding margin.

Second, to provide a temporary binder or loose sheet holder having these advantages in which the sheet body is very securely held even in binders of large dimensions and a thick sheet body.

Third, to provide a temporary binder or loose sheet holder which is adapted for sheets originally intended for the post type of binders.

Objects relating to details and economies of the invention will appear from the description to follow. The invention is defined and pointed out in the claims.

A preferred embodiment of the invention is illustrated in the accompanying drawings, in 20 which:

Fig. 1 is a perspective view of a temporary binder or loose sheet holder embodying the invention.

Fig. 2 is an enlarged fragmentary view on line 25 2—2 of Fig. 1.

Fig. 3 is an enlarged fragmentary view on line 3—3 of Figs. 1 and 4.

Fig. 4 is a detail section on line 4—4 of Fig. 3.

Fig. 4-A is a detail section on line 4-A—4-A 30 of Fig. 4.

Fig. 5 is a fragmentary perspective view of the binder in open position sectioned, the section corresponding to that of Fig. 2.

Fig. 6 is a fragmentary plan view with one of 35 the covers in open position.

Fig. 7 is a perspective view of the sheet body removed from the binder, one of the post bars being partially removed from the sheet body.

Fig. 8 is a detail view illustrating the telescoping post type of post bars, the sheet body being indicated by dotted lines.

Fig. 9 is a perspective view of one of the cover hinge members.

Fig. 10 is a perspective view of one of the 45 clamping bar hinge plates or members.

In the embodiment of my invention illustrated, the covers 1 and 2 are of suitable structure and dimensions to accommodate the sheet body conventionally shown at 3. The clamping bars designated by the numeral 4, in the preferred embodiment illustrated, comprise the outer non-metallic relatively thick elements 5 and the inner metal plates 6, the elements being secured together by the screws 27.

The outer binder bar elements 5 have slot-

like recesses 8 extending from their inner edges, the rear ends of the slots being adjacent the rear edges of the elements 5 as shown in Fig. 3.

The plates 6 have slots 7 opening to the recesses 8, these slots being arranged quite close to the rear edges of the plate 6 or, in other words, quite close to the rear edges of the clamping bars. The purpose of this will appear as the description proceeds. The plates 6 extend across the recesses closing their inner sides and also reinforcing the elements 5 so that the completed clamping bar has the desired strength and rigidity.

The clamping bars are provided with hinge plates 9, those illustrated being of channel section and secured to the plate 6 in an outwardly facing relation within the recesses by spot-welding at 29.

The covers are provided with arm-like hinge members 10 preferably of channel cross section disposed with the channels facing inwardly and with the flanges thereof pivoted to the flanges of the hinge plate by means of the pivots 11. It will be noted that these pivots are located well to the rear of the center of the clamping bars 25 but somewhat in advance of the slots 7—see Fig. 3.

The hinge members 10 are preferably inwardly offset at 12 so that they may be secured on the inner sides of the covers and the outer sides 30 of their projecting portions are approximately flush with the outer sides of the covers and with the clamping bars when the parts are in closed position.

The flexible binding members 13 are secured 35 at one end to the cover 1 as by means of the rivets 14, their other ends being secured to the adjusting member 15 carried by the cover 2. As the details of the adjusting means form no part of this invention they are not further described herein. It will be noted by reference to Fig. 3 that these binding members are disposed longitudinally within the hinge members 10 to pass through the slots 7 in the faces of the clamping bars and that the reaches thereof extending between the clamping bars lie at the rear of the rear edges or end of the sheet body 3 as distinguished from being engaged within slots of the binding member receiving openings in the sheets.

The clamping bars are provided with sockets 16 positioned to receive the pins 17 on the post bars 18. These post bars are provided with non-aligned posts 19 engageable with holes 20 provided therefor in the sheets. In the embodiment 55

illustrated, the pins 17 are located well toward the edges of the post bars, a part of them, the outer pins in the embodiment illustrated, being closely adjacent the front edges of the post bars and the center or intermediate pin being closely adjacent to the rear edges of the post bars.

The posts 19 are closely adjacent the front or inner edges of the post bars as best shown in Fig. 2, and it will also be noted that the post bars 10 and the entire sheet body lie in front of the reaches of the binding members extending between the clamping bars. By this staggered relation of the pins or studs 17 on the post bars, the tendency of the post bars to rock on the clamping bars is minimized or, in other words, their engagement is stabilized against the various stresses to which they are subject in the manipulation of the binder.

The position of the binding members relative to the post bars and to the clamping bars 20 further results in holding the parts in position notwithstanding the relatively narrow binding margin of the sheets.

To urge the inner edges of the post bars inwardly upon the sheets, the webs of the hinge plates 9 are provided with supports 21 for the binding members, see Fig. 3, these supports being in the form of outwardly disposed bead-like rolls on the front edges of the web portions of the hinge members 9, see Fig. 3.

This arrangement of parts insures a clamping stress of the binding members upon the inner edges of the clamping bars when the binder is closed and further stabilizes the clamping bars and post bars in their relation the one to the other.

In Fig. 8, I illustrate an embodiment in which the post bars are provided with telescoping post members 22 and 23.

My improved binder is adapted for receiving sheets designed for post binders of various types, it only being necessary to space the posts to correspond to the spacing of the holes 20 in the sheets. The sheets are effectively bound by a relatively narrow binding margin which of course is a desirable factor as a larger proportion of the sheets may be utilized for recording purposes or the sheets may be of less length for the same amount of writing surface as compared to the average post binder or binder of this general type now on the market.

I have illustrated and described my improvements in highly practical embodiments thereof.

Having thus described my invention, what I claim as new and desire to secure by Letters Patent is:

1. In a temporary binder or loose sheet holder, the combination with covers, of clamping bars having post bar sockets in their inner sides and comprising relatively thick outer elements having recesses extending from their front edges to a point adjacent their rear edges and inner plate-like elements secured to the inner sides of said outer elements and extending across said recesses therein and having slots therethrough adjacent their rear edges opening to said recesses, channel-shaped hinge plates mounted on said inner elements of said clamping bars within said recesses facing outwardly, the front edges of the web portions of said hinge plates being formed into rounded outwardly disposed binding member supports, arm-like cover hinge members of channel cross section secured to said covers to project from their rear edges into said recesses of said clamping bars and having the rear ends of their

flanges pivoted between the rear ends of the flanges of said hinge plates, the front ends of said cover hinge members being inwardly offset to receive the rear edges of the covers, flexible binding members extending between said covers and disposed longitudinally within said cover member hinge members over said binding member supports on said hinge plates and through said slots in said clamping bar plates, the slots being at the rear of the pivots so that when the clamping bars are in closed position upon the body of sheets the reaches of the binding members extending between the clamping bars lie in a plane at the rear of the plane of the clamping bar pivots and substantially at the rear of a plane 15 centrally through the clamping bars, and post bars provided with sheet engaging posts and with clamping bar socket engaging pins disposed with part of the pins adjacent the front edges of the post bars and part of them adjacent the rear edges of the post bars and acting to stabilize the post bars in relation to the clamping bars, the posts of said post bars being positioned adjacent the front edges of the post bars when the binder is closed and in a plane adjacent the front edges of the clamping bars whereby a sheet body may be bound with its rear edge and the rear edges of said post bars in front of the reaches of the flexible binding members extending between the clamping bars.

2. In a temporary binder or loose sheet holder, the combination with covers, of clamping bars having post bar sockets in their inner sides and comprising relatively thick outer elements having recesses extending from their front edges to a point adjacent their rear edges and inner plate-like elements secured to the inner sides of said outer elements and extending across said recesses therein and having slots therethrough adjacent their rear edges opening to said recesses, hinge plates mounted on said inner elements of said clamping bars within said recesses, arm-like cover hinge members secured to said covers to project from their rear edges into said recesses of said clamping bars and having their rear ends pivoted to said hinge plates, flexible binding members extending between said covers and through said slots in said clamping bar plates, the slots being at the rear of the pivots so that when the clamping bars are in closed position upon the body of sheets the reaches of the binding members extending between the clamping bars lie in a plane at the rear of the plane of the clamping bar pivots and substantially at the rear of a plane centrally through the clamping bars, and post bars provided with sheet engaging posts and with clamping bar socket engaging pins disposed with part of the pins adjacent the front edges of the post bars and part of them adjacent the rear edges of the post bars and acting to stabilize the post bars in relation to the clamping bars, the posts of said post bars being positioned adjacent the front edges of the post bars when the binder is closed and in a plane adjacent the front edges of the clamping bars whereby a sheet body may be bound with its rear edge and the rear edges of said post bars in front of the reaches of the flexible binding members extending between the clamping bars.

3. In a temporary binder or loose sheet holder, the combination with covers, of clamping bars having post bar sockets in their inner sides and comprising relatively thick outer elements having recesses extending from their front edges to a point adjacent their rear edges and inner plate-

- like elements secured to the inner sides of said outer elements and extending across said recesses therein and having slots therethrough adjacent their rear edges opening to said recesses, channel-shaped hinge plates mounted on said inner elements of said clamping bars within said recesses facing outwardly, the front edges of the web portions of said hinge plates being formed into rounded outwardly disposed binding members 5 supports, arm-like cover hinge members of channel cross section secured to said covers to project from their rear edges into said recesses of said clamping bars and having the rear ends of their flanges pivoted between the rear ends of 10 the flanges of said hinge plates, the front ends of said cover hinge members being inwardly offset to receive the rear edges of the covers, flexible binding members extending between said covers and disposed longitudinally within said 15 20 cover member hinge members over said binding member supports on said hinge plates and through said slots in said clamping bar plates, and post bars provided with sheet engaging posts and with clamping bar socket engaging pins, the 25 posts and clamping bar engaging pins being disposed so that a sheet body may be bound with its rear edge and the rear edges of said post bars in front of the reaches of the flexible binding members extending between the clamping bars.
4. In a temporary binder or loose sheet holder, the combination with covers, of clamping bars having post bar sockets in their inner sides and comprising relatively thick outer elements having recesses extending from their front edges to a 30 point adjacent their rear edges and inner plate-like elements secured to the inner sides of said outer elements and extending across said recesses therein and having slots therethrough adjacent their rear edges opening to said recesses, 35 hinge plates mounted on said inner elements of said clamping bars within said recesses, arm-like cover hinge members secured to said covers to project from their rear edges into said recesses of said clamping bars and having their rear ends 40 pivoted to said hinge plates, flexible binding members extending between said covers and through said slots in said clamping bar plates, and post bars provided with sheet engaging posts and with clamping bar socket engaging pins, the 45 posts and clamping bar engaging pins being disposed so that a sheet body may be bound with its rear edge and the rear edges of said post bars in front of the reaches of the flexible binding members extending between the clamping bars.
5. In a temporary binder or loose sheet holder, the combination with covers, of clamping bars having post bar sockets in their inner sides and hinge recesses extending from their front 50 edges and slots adjacent their rear edges opening to said recesses, arm-like cover hinge members pivotally mounted at their rear ends within said recesses, flexible binding members extending between said covers and disposed through said slots in said clamping bars, the slots and pivots being 55 so disposed relative to each other that when the clamping bars are in closed position upon the body of sheets the reaches of the binding members extending between the clamping bars lie in a plane at the rear of the plane of the clamping bar pivots and substantially at the rear of a plane centrally through the clamping bars, and post bars provided with sheet engaging posts and clamping bar socket engaging pins, the posts and clamping bar engaging pins being disposed so 60 that a sheet body may be bound with its rear edge and the rear edges of said post bars in front of the reaches of the flexible binding members extending between the clamping bars.
6. In a temporary binder or loose sheet holder, the combination with covers, of clamping bars having post bar sockets in their inner sides and hinge recesses extending from their front edges and slots adjacent their rear edges opening to 65 said recesses, arm-like cover hinge members pivotally mounted at their rear ends within said recesses, flexible binding members extending between said covers and disposed through said slots in said clamping bars, and post bars provided with sheet engaging posts and clamping bar socket engaging pins, the posts and clamping bar engaging pins being disposed so 70 that a sheet body may be bound with its rear edge and the rear edges of said post bars in front of the reaches of the flexible binding members extending between the clamping bars.

of the flexible binding members extending between the clamping bars.

9. In a temporary binder or loose sheet holder, the combination with covers, of clamping bars having post bar sockets in their inner sides, arm-like cover hinge members on which said clamping bars are pivotally mounted, flexible binding members extending between said covers and disposed through said clamping bars, and post bars 5 provided with sheet engaging posts and clamping bar socket engaging pins disposed with part of the pins adjacent the front edges of the post bars and part of them adjacent the rear edges of the post bars and acting to stabilize the post bars in relation to the clamping bars, the posts of said post bars being positioned adjacent the front edges of the post bars when the binder is 10 closed and in a plane adjacent the front edges 15 of the clamping bars whereby a sheet body may

be bound with its rear edge and the rear edges of said post bars in front of the reaches of the flexible binding members extending between the clamping bars.

10. In a temporary binder or loose sheet holder, 5 the combination with covers, of clamping bars having post bar sockets in their inner sides, arm-like cover hinge members on which said clamping bars are pivotally mounted, flexible binding members extending between said covers and disposed through said clamping bars, and post bars provided with sheet engaging posts and clamping bar socket engaging pins, the posts and clamping bar engaging pins being disposed so that a sheet body may be bound with its rear 10 edge and the rear edges of said post bars in front 15 of the reaches of the flexible binding members extending between the clamping bars.

LEON L. ALLYN.
